UNITED STATES PATENT OFFICE.

HENRY A. WEIHMAN, OF PHILADELPHIA, PENNSYLVANIA.

DESIGN FOR A THIMBLE.

SPECIFICATION forming part of Design No. 19,750, dated April 1, 1890.

Application filed February 13, 1890. Serial No. 340,367. Term of patent 14 years.

To all whom it may concern:

Be it known that I, HENRY A. WEIHMAN, of the city and county of Philadelphia, and State of Pennsylvania, have invented a new 5 and original Design for Thimbles, of which the following is a specification.

My invention has reference to a new design for thimbles, which design is fully set out in the following specification and shown in the 10 accompanying drawings, which form a part thereof.

My design has particular reference to the ornamentation given to the lower or rim portion of the thimble, which will be best understood by examining the accompanying illustration, in which—

Figure 1 is an elevation of a thimble embodying my new design, and Fig. 2 is a plan view of the surface of the thimble laid out flat. 15
20 A is the lower or rim portion, upon which is placed my new ornamentation. B is the

upper cylindrical walls having the indented work, and C is the top or crown of the thimble.

F is an annular groove about the thimble, between the parts A and B; but this is unimportant to the design. The part A is chased or embossed with the design shown, which is composed, essentially, of the name-plate or escutcheon D and the scenic effect E, consisting of houses, a river, a bridge, trees, and distant 25 30 mountains, substantially as shown.

Having now described my invention, what I claim as new, and desire to secure by Letters Patent, is—

The new design for thimbles, substantially 35 as herein described and shown.

In testimony of which invention I have hereunto set my hand.

HENRY A. WEIHMAN.
